(57) **CLAIM**

The ornamental design for a bottle, as shown and described.

DESCRIPTION

FIG. 1 is a perspective view of a bottle showing our new design;

FIG. 2 is a front view thereof, a rear view being a mirror image of the front view;

FIG. 3 is a left side view thereof;

FIG. 4 is a right side view thereof;

FIG. 5 is a top view thereof;

FIG. 6 is a bottom view thereof;

FIG. 7 is a perspective view thereof in a configuration without a cap; and,

FIG. 8 is a front view thereof in the configuration without the cap.

The dot-dash broken lines depict boundary of the claimed design and form no part of the claimed design.

1 Claim, 4 Drawing Sheets(56)
